JAMES, OF NEW YORK, N. Y.

INTERNAL COMBUSTION ENGINE

Application filed November 6, 1930. Serial No. 493,870.

This invention relates to internal combustion engines, and more particularly to Diesel engines of the two-cycle type.

An object of the invention is to provide an engine having a stationary block enclosed in a rotary casing in which air is drawn through inlet valves in the casing, and compressed by the pistons in the block to supply the necessary charge and scavenge the engine.

A further object is to provide an engine of this character in which radially positioned pistons in the block have valves in their heads which open on the extreme outward movement of the pistons, and admit air through the pistons to eject the burnt gases.

A further object is to provide an engine such as above described, in which an air inlet valve is located in alignment with the inner ends of the cylinders, which is opened by the action of the pistons when pressure falls in the cylinders.

A further object is to provide an engine of this character in which there is full and complete scavenging and an entrapment of pure air on the inward strokes of the pistons.

A further object is to provide an engine of this character in which the exhaust and scavenging take place when the pistons are near the outer ends of their strokes, or what is commonly known as "bottom dead center", and consequently only very small portions of the expansion and compression strokes are lost.

A further object is to provide an engine of this character in which the parts are balanced and symmetrical, and reciprocating motion of the pistons is transformed into rotary motion of the casing so that power may be taken off at the bearing at one end of the casing and from the periphery of the casing.

In the accompanying drawings,
45 Figure 1 is a view in longitudinal section

of my improved engine showing the pistons in firing position;

Figure 2 is a view in longitudinal section on a somewhat reduced scale on the line 2—2 of Figure 1;

Figure 3 is a view in longitudinal section through the engine block, showing the pistons in their extreme outward positions and illustrating the admission of air through the several ports, the view being more or less 55 diagrammatic; and

Figure 4 is a broken sectional view on the line 4—4 of Figure 3.

My improved engine comprises an engine block, indicated as a whole by the reference character A, which is of general circular form, and has cylindrical enlargements 1 and 2 at its respective ends constituting stubs on which cylindrical bearing sleeves 3 and 4, respectively, of my improved casing B are 60 mounted to turn.

It is to be understood that the block A is stationary and may be rigidly supported by suitable frame-work 5 at the end of the enlargement 1, and a frame-work 6 may be provided at the opposite side of the engine having a bearing sleeve 7 in which the bearing sleeve 4 turns.

The engine block A is formed with a series of (preferably four) radial bores constituting engine cylinders 8 in which working pistons 9 are mounted to reciprocate. As all of the cylinders and the working pistons and co-operating elements of all the cylinder units are precisely alike, the same reference characters will be employed to indicate like parts in each of the cylinder and piston assemblies.

The casing, indicated generally by reference character B, comprises a central or intermediate annular ring 10 to which side plates 11 and 12 are secured in any approved manner. The intermediate ring portion 10 of the casing B is formed with an annular internal lubricant chamber 13, which has con-

verging flanges or walls 14 spaced apart to provide a slot 15 all around the casing and in open communication with the interior thereof.

This ring portion 10 of the casing B is formed with two spaced circular series of pins 16 constituting racks. I would call particular attention to the construction of mounting for these pins 16 which facilitates their removal and replacement in the event of injury, and assures a strong and durable structure.

The pins 16 are preferably made from a high grade steel, heat treated, hardened and ground full surface. They have a two-step taper and extend across a groove 17 in the ring 10, said groove being connected by lubricant ducts 18 with the lubricant chamber 13. The two-step taper pin is inserted in place by a snug driving fit and same held in place by a screwed dowel or pipe plug 19. The outer plates of the casing, 11 or 12 as the case may be, bear against the outer ends of the pins and prevent any possibility of their displacement, but in the event a pin is broken the casing plate may be removed and a new pin inserted.

Connecting rods 21 connect pins 22 carried by the pistons 9 with crank pins 23 connecting pairs of toothed wheels 24. These toothed wheels mesh with the racks formed by the pins 16, but more specifically with the rollers 20 carried by said pins, and a reciprocating motion of the pistons imparts rotary motion to the toothed wheels 24, and the latter transmit rotary motion to the casing B.

The connecting rods 21 have longitudinal lubricant ducts 25 therein which communicate with bearing sleeves 26 and 27 on the pins 22 and 23, respectively. The crank pins 23 have longitudinally extending lubricant ducts 28 communicating with bearings 29 in the engine block A, in which axle stubs 30 on the toothed wheels 24 have rotary mountings. The extremity of the connecting rod 21 has an opening or entrance 31 for the lubricant which is caught up by the connecting rod in its motion so that lubricant is supplied to the several bearings by the action of the engine.

Of course, it will be understood that the turning movement of the engine maintains the lubricant normally in its chamber 13 by centrifugal force, and this lubricant is more or less under agitation so that the movement of the several parts insures a proper lubrication of the bearings.

It will be particularly noted by reference to Figure 2 of the drawings, that all of the engine cylinders 8 communicate at the center of the engine block, and that all of the pistons 9 have tapered inner ends or heads 32 with slightly curved extremities so that at the extremity of their inward strokes a relatively small space 33 is provided, and radial spaces

are provided between the pistons so as to insure an efficient operation after ignition and during the working strokes of the pistons.

The pistons 9 are provided in their working faces with check valves 34 for a purpose which will more fully hereinafter appear.

The engine block at its center and at one side thereof is formed with an air chamber 35 in open communication with all of the cylinders and with the space 33 above referred to. The outer wall of this chamber 35 has air inlet ports 36 which are normally closed by a check valve 37 opening inwardly. The ports 36 all communicate with radial passages 38, the ends of which constitute ports 39 communicating with the interior of the cylinders 8.

At this same side of the engine, where the valve 37 and passages 38 are located, a roller or other anti-friction thrust bearing 40 is provided between the enlargement 2 of the engine block A and a disk-like head 41 fixed to the bearing sleeve 4 of the engine casing B. A relatively large air chamber 42 is formed in the end of the enlargement 2, and a fan or blower 43 is located in a fan chamber 44 in the head 41.

A series of radial air inlet ports 45 are provided in the head 44 and communicate with the air chamber 42.

The fan or blower casing 44 has exhaust ports 47 in its walls through which air is drawn out of the chamber 42 by the action of the fan 43, and it will be understood that as the fan revolves a continuous flow of swirling air will be had within the chamber 42 to maintain the bearing cool.

The head 41 has an extension 49 thereon to which one end of a shaft 50 is fixed, and this shaft constitutes the driving shaft of the engine, although it is also possible to take off power from the periphery of the casing B.

The engine block A at the side thereof opposite to the valve 37 is formed with a chamber or space 51 in open communication with the interior of all of the cylinders and with the space 33 above referred to. An injection nozzle 52 is mounted in the enlargement 1 and communicates with the space or chamber 51.

The casing B is provided with air inlet check valves 61 and air escape governing valves 62. The valves 61 open inwardly and the valves 62 open outwardly, and said valves 62 are appreciably smaller and control smaller ports than do the valves 61, and are useful only in preventing over-pressure within the engine casing.

The engine block A may have any suitable arrangement of water jackets 63 in communication with inlet and outlet passages 64 and 65, respectively, and a normally closed inlet 66 may be provided in the enlargement 1 for the insertion of lubricant into the casing,

or for the attachment of air pressure means to give the air within the casing a normal initial pressure, such as may be desired.

The engine block A is provided in one side thereof with passages 67, which are exhaust passages, each of which connects a pair of cylinders 8, and the ends of said passages constitute exhaust ports 68 which are opened and closed by the working pistons 9.

These passages 67 communicate with exhaust manifolds 69 for free exhaust of the burnt gases. The passages 67 and the manifolds 69 are in the side of the block opposite to that side of the block in which the passages 38 are located.

The operation of my improved engine as above described is as follows:

Figures 1 and 2 illustrate the pistons in their extreme inward positions, which are, of course, the firing positions in a two-cycle engine. In this position, where the engine is of the Diesel type, the air is under the proper pressure so that when there is a fuel injection from the nozzle 51 the charge will burn, and expand and force the pistons outwardly, constituting the working strokes of the pistons.

It will be noted that the air passages 41 communicate with the ends of the cylinders 4 at a point where they are open at all times, so that the pressure within these passages is never lower than the pressure within the casing. During the working stroke of the pistons the valves 37 and 34 are maintained in closed position by the pressure within the cylinders.

When the pistons near the extremes of their outward strokes they uncover or open the passages 67, so that the exhaust gases rush through these passages and through the manifolds 69 instantly lowering the pressure in the space between the pistons.

The outward movement of the pistons increases the pressure of air within the casing so that as these pistons move outwardly and the pressure falls within the space between the pistons, due to the exhaust of the burnt gases through the passages 67, the air inlet valve 37 will be opened and the air will rush into the space between the pistons and through the cylinders to force out the burnt gases through the passages 67.

As the pressure in the casing becomes greater than the pressure between the pistons the valves 34 in the piston heads will also open so that there will be an inrush of air through the pistons, as well as past the valve 34, to completely scavenge the engine and provide a fresh charge of air for compression on the inward or compression strokes of the pistons.

The positions of the several valves, pistons, etc., on the outward strokes of the pistons are illustrated in Figures 3 and 4 of the drawings, the taper of the pistons being such

that while the inward extremities of the pistons are beyond the ports 68 of passages 67, the wide walls of said pistons are beyond the said passages of the ports, as indicated clearly in Figure 4 of the drawings.

In a very real sense the opening of the valves 34 in the piston heads admits a supercharge of fresh air which is compressed to a maximum degree within the casing by the outward movement of the pistons, so that as the pistons begin their inward strokes the air entrapped between the pistons is at a relatively high pressure so that the inward movements of the pistons bring the pressure to a degree sufficient for Diesel engine operation.

It is my belief that the casing, by reason of these rapid revolutions, induces by centrifugal or centripetal force an intake of air which is also an aid to higher air compression, which is desirable and which varies in accordance with the speed of the engine.

While I have illustrated what I believe to be the preferred embodiment of my invention, it is to be distinctly understood that various slight changes may be made with regard to the form and arrangement of parts without departing from my invention, and hence I do not limit myself to the precise details set forth but consider myself at liberty to make such changes and alterations as fairly fall within the spirit and scope of the claims.

What I claim is:

1. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passages to the space between the pistons, said block having exhaust passages therein opened by the pistons on their outward strokes, and valves in the heads of the pistons.

2. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passages to the space between the pistons, said block having exhaust passages therein opened by the pistons on their outward strokes, and valves in the heads of the pistons, said valves opened by the pressure of air back of them, the valves in the pistons opening to admit air under highest compression within the casing, whereby a two stage scavenging action is had.

3. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passage to the space between the pistons, said block having exhaust passages therein opened by the pistons on their outward strokes, and valves in the heads of the pistons, said pistons having tapering inner heads, the valves of the pistons located in the extremities of said tapering heads.
4. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passages to the space between the pistons, said block having exhaust passages therein opened by the pistons on their outward strokes, and valves in the heads of the pistons, said valves opened by the pressure of air back of them, the valves in the pistons opening to admit air under highest compression within the casing.
5. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passages to the space between the pistons, said block having exhaust passages therein opened by the pistons on their outward strokes, valves in the heads of the pistons, said exhaust passages each connecting two of the cylinders, and exhaust manifolds communicating with said passages.
6. A two-cycle internal combustion engine including a block having radially arranged cylinders communicating at their inner ends, pistons mounted to reciprocate in the cylinders, an air-tight casing mounted to turn on the block, enclosing the block and to which rotary motion is imparted by the pistons, said block having air passages communicating with the interior of the casing, a check valve admitting air from said passages to the space between the pistons, said block having exhaust passages therein opened by the pistons on their outward strokes, valves in the heads of the pistons, said valves opened by the pressure of air back of them, the valves in the pistons opening to admit air under highest compression within the casing.

pistons opening to admit air under highest compression within the casing, said exhaust passages each connecting two of the cylinders, and exhaust manifolds communicating with said passages.

70

7. An engine as set forth in claim 1, including check valves controlling an inlet of air to the cylinder, and a fuel inlet nozzle communicating with the space between the pistons.

8. An internal combustion engine of the two-cycle type comprising a block having communicating radially positioned cylinders therein, pistons mounted to reciprocate in the cylinders, exhaust passages in the block connecting each and all of said cylinders and normally opened by the pistons only when the latter are adjacent their outward extreme of movement, and check valves in the pistons opened by air pressure which rushes through the pistons as the pistons reach the ends of their outward strokes.

75

9. An internal combustion engine of the two-cycle type comprising a block having communicating radially positioned cylinders therein, pistons mounted to reciprocate in the cylinders, exhaust passages in the block connecting each and all of said cylinders and normally opened by the pistons only when the latter are adjacent their outward extreme of movement, and check valves in the pistons opened by air pressure which rushes through the pistons as the pistons reach the ends of their outward strokes, said pressure of air being caused by the outward movement of the pistons.

90

10. An internal combustion engine of the two-cycle type comprising a block having communicating radially positioned cylinders therein, pistons mounted to reciprocate in the cylinders, passages connecting each of said cylinders and normally opened by the pistons only when the latter are adjacent their outward extreme of movement, check valves in the pistons opened by air pressure which rushes through the pistons as the pistons reach the ends of their outward strokes, a rotary casing mounted in the block and to which rotary movement is imparted by the pistons, said casing constituting an air chamber in which air is compressed by the movement of the pistons.

105

11. An internal combustion engine of the two-cycle type comprising a block having communicating radially positioned cylinders therein, pistons mounted to reciprocate in the cylinders, passages connecting each of said cylinders and normally opened by the pistons only when the latter are adjacent their outward extreme of movement, and check valves in the pistons opened by air pressure which rushes through the pistons as the pistons reach the ends of their outward strokes, said casing having inlet and outlet check valves, whereby the rotary motion of the casing induces an intake of air thereto,

110

120

125

130

whereby a two stage scavenging action is had.

12. An internal combustion engine of the two-cycle type including a stationary block, a rotary hollow air-tight casing mounted to
5 turn on the block, reciprocating pistons in the block having a common compression chamber, passages in the block in open communication with the casing, a check valve controlling the entrance of air from said passages to
10 the compression chamber, exhaust passages in the block controlled by the pistons, and super-charging valves in the heads of the pistons open only as the pistons reach the extreme of their outward movements.
